CONTAINER FOR DENTAL AMALGAMS

Peter Doll, Bad Godesberg, Germany

Application September 15, 1936, Serial No. 100,824
In Germany September 23, 1935

8 Claims.

(Cl. 259—1)

It is known to store the separate constituents of dental amalgams, namely mercury and particles of metal, such as powder, foil, filings and the like, in separate containers in the quantities in which they are required to be mixed together. These containers may in some cases be combined to form a unit or may be in the form of cellular gelatine containers. The materials are then available to the dentist in handy form and he can make an amalgam containing the constituents in the correct proportions by emptying the different containers or the various cells of one and the same container without it being necessary for him to measure out the quantities.

A great disadvantage of such containers is that they must be emptied for the purpose of mixing and preparing the amalgam and in doing this a loss of material may easily occur, which may result in the materials not being mixed in the proper proportions and, therefore, in the quality of the amalgam being impaired. Also, the amalgam mixture either has to be kneaded by hand, in which case mercury is either rubbed into the skin or else separate mixing devices constituting additional apparatus are required.

All these difficulties and disadvantages are obviated by means of the container for storing and mixing the separate constituents of dental amalgams in accordance with the invention, in which the quantities of mercury and metal particles are stored in their correct proportions and separately from each other; the novel container, however, enables the constituents to be combined and mixed to form the desired amalgam without the hand of the dentist coming into contact with the amalgam or any auxiliary apparatus being necessary for the mixing.

This container in accordance with the invention comprises a bulb-like portion of flexible material, for example of rubber or the like for the reception of the metal powder or filings and a vessel of glass or the like for the reception of the mercury. The open end of the flexible bulb is attached to the head of the mercury vessel. This vessel is provided with a piston, by means of which it is normally closed. The free end of this piston projects out of the glass vessel and on being pressed inwards uncloses an opening for the access of the mercury to the flexible bulb, in which the components of the amalgam are then mixed together and can be amalgamated to form the desired exactly proportioned amalgam. After the amalgamation, the dentist can, by means of a plug or the like, remove the product from the bulb which has been removed or cut

off from the hollow body and is held between the tips of the fingers, so that none of the amalgam comes into direct contact with the skin, which is of extreme importance for avoiding injury to health and impairing the composition.

The mercury vessel is preferably in the form of a cylindrical tube of glass or the like which is thickened at its head, and in order to improve the degree of security with which the free end of the bulb portion which is drawn on it is held. The bulb portion is also preferably thickened at its open end for enabling it to be secured to the glass tube.

The tube from which the mercury vessel is made is open at both ends, the openings being closed by packing discs of cork, rubber or the like, and preferably of paraffined cork. The disc which is remote from the flexible tube seems to guide the free end of the piston, which can slide through it when it is moved. The working end of the piston acts on the other disc, and can be caused to open the bulb end of the glass tube when desired. In the form of construction of the invention which has just been described, it is particularly advantageous to construct the latter disc as an annular disc and to mount this on the working end of the piston and to secure it in this position by an adjacent thickening on one or both sides of the piston.

The flexible bulb is preferably provided with one or more air outlets, for example small holes preferably near the connection to the mercury vessel to enable the air to escape when the components are kneaded in the bulb, the kneading being thus facilitated and the amalgamation being made particularly rapid and intimate.

Instead of providing the bulb part with air outlets, it is also possible for the same purpose instead of a massive piston, as a total glass piston, to use a piston with an opening longitudinally passing through, as for instance a glass capillary tube, which in turn makes possible a ventilating of the bulb part, too.

An embodiment of the invention is illustrated diagrammatically by way of example in the accompanying drawing, which serves to illustrate the construction of a device in accordance with the invention, its use and advantages.

Figures 1 and 2 show the said embodiment in axial section, Figure 1 illustrating the normal or storage condition and Figure 2 the position taken up by the parts when the contents of the compartments are to be mixed.

Figure 3 is an outside elevation of the device, one end having been cut off, and

Figure 4 shows the part that has been cut off from the device of Figure 3.

In Figure 1, 1 is a bulb of flexible material which is made, in this case, in the form of a small rubber capsule which contains a measured quantity of metal filings 2 and is provided at its open end with a thickened portion 3. This open end is drawn on the end 4 of a cylindrical glass tube 5 which is thickened at its end 4. A piston 6, preferably made of glass, is provided in this tube 5. It supports at its working end an annular packing disc 7 made of paraffined cork or the like which is secured in the position by the thickened part 8. The rod of this piston 6 is carried through an annular packing disc or closure member 9 of paraffined cork which closes the end of the tube 5 remote from the bulb 1, and thus forms with the packing disc 7 a hollow space inside the tube 5 in which is stored the quantity of mercury 10 which is measured to correspond to the filings 2.

For combining the two components of the amalgam it is only necessary to push in the free end of the piston 6 and thereby to push the head 25 of the piston itself slightly into the tube, the bulb 1 being preferably held downwards. The packing disc 7 is thus removed out of the opening 11 in the tube 5 (Figure 2) so that a passage is formed between the tube and the bulb 1 through 30 which the mercury 10 can enter the latter to be combined there with the filings 2.

The components 2 and 10 of the amalgam are then amalgamated in the bulb 1 by kneading them together. This is facilitated by the provision of one or more air outlets, such as small holes 12 (Figure 3) in the bulb, preferably near its open end. After the amalgamation, the bulb 1 merely needs to be pulled off from the hollow body 5, or cut off (Figures 3 and 4), the desired 40 product being then contained in a single small vessel which can be held easily between the finger tips. The product can then be taken out with a suitable instrument, for example a plug, direct contact with it being avoided. In this 45 way, absolutely correct measurement of the proportions is ensured, loss of material and, therefore, impairment of the qualities of the amalgam is avoided, and any troublesome weighing becomes superfluous. Further, direct contact 50 with the hand of the dentist is prevented, as a container is provided which allows the individual

constituents to be stored separately and enables a faultless preparation of the amalgam to be made.

I claim:

1. A container comprising a flexible bulb, a tube closed at one end, a thickened portion adjacent the open end of said bulb, a thickened portion adjacent the open end of said tube, said thickened portion of said tube lying within said bulb and on the side of said thickened portion 10 of said bulb nearer to the closed end of said bulb and means for putting the inside of said bulb and the inside of said tube into and out of communication with each other.

2. A container comprising a flexible bulb, a rigid tube engaged in the open end of said bulb, a piston in said tube, a closure member at the end of said tube remote from said bulb, said closure member being traversed by the rod of said piston.

20 3. A container as claimed in claim 2, in which said piston comprises a substantially cylindrical portion of substantially the same diameter as said tube, a cylindrical portion of reduced diameter and an annular disc of substantially the same diameter as said tube mounted on said portion of reduced diameter.

4. A container as claimed in claim 2, in which said flexible bulb is provided with air outlets.

5. A container according to claim 2, in which 30 is provided an air outlet disposed longitudinally through said piston.

6. A container as claimed in claim 2, in which said bulb is provided with air outlets formed adjacent its connection to said tube.

35 7. A container for the constituents of dental amalgam suitable also for amalgamating said constituents, comprising a rubber bulb, a glass tube connected internally to said bulb, closure means at the end of said tube remote from said bulb and a piston having its head located in said tube and its rod projecting through said closure member.

8. A container comprising a bulb made of a flexible material, a tube closed at one end and 45 connected at its open end to the open end of said bulb, a stopper in said tube adjacent its open end and means for displacing said stopper whereby to put the inside of said tube and of said bulb into communication with each other.
